UNITED STATES PATENT OFFICE.

WILLIAM GILBERT, OF ALBANY, MISSOURI.

GAME APPARATUS.

SPECIFICATION forming part of Letters Patent No. 607,031, dated July 12, 1898.

Application filed July 14, 1897. Serial No. 644,524. (No model.)

To all whom it may concern:

Be it known that I, WILLIAM GILBERT, residing at Albany, in the county of Gentry and State of Missouri, have invented a Game Apparatus, of which the following is a specification.

My invention relates to games, and more particularly to games played upon a table or board with balls to be propelled by cues or disks to be propelled by the fingers.

The object of my invention is to produce a new and interesting game of this class; and with this object in view my invention consists in a game-board provided with surrounding cushions, corner receptacles for balls to be played with, marks for distinguishing the stations from which the balls or disks are to be started, and marks to distinguish certain lines and stations to which the balls are to be propelled, and pockets covered with rubber to form cushions against which the balls may be banked during the playing of the game.

My invention further consists in the improved details of construction, arrangement, and combination of parts hereinafter fully described, and afterward specifically pointed out in the claims.

In order to enable others skilled in the art to which my invention most nearly appertains to make and use the same, I will now proceed to describe and illustrate its construction and operation in connection with the accompanying drawings, forming a part of this specification, in which--

Figure 1 is a plan view of the game-table constructed in accordance with my invention. Fig. 2 is a vertical section through slightly more than one-half of the table on the line 22 of Fig. 1. Fig. 3 is a detail sectional view showing the construction of the cushions. Fig. 4 is a sectional view similar to Fig. 2 through a portion of a modified form of board for use with disks only. Fig. 5 is a detail sectional view to illustrate the cushion on the board shown in Fig. 4. Fig. 6 is a top plan view of one of the slides covering the pockets. Fig. 7 is a detail view showing a sheet-iron pocket, such as used in the modified form of table shown in Figs. 4 and 5, attached to the rail.

The base or foundation of my game-table is

composed of two layers A A' of hard wood, and preferably covered with oil-cloth, billiard-cloth, or similar material. The four corners 55 are cut off, as at B, to form receptacles for the balls not in use.

Cushions C, C', C², and C³ entirely surround the table, except where interrupted by pockets D, D', D², and D³, one in the center of 60 each side. These cushions are composed of rubber or other suitable material set up inside the walls E, E', E², and E³, being cemented or otherwise properly secured thereto.

The lower portions C⁴ of the inner face of 65 the cushions are perpendicular for about one-half the height thereof, the upper half from this point being inclined inward to an acute-angled edge C⁵, as substantially shown in Fig. 3.

The pockets D are made by attaching semi-circular metal brackets F at the proper positions to project beyond the sides of the table, these brackets being covered with leather, as at F', and suspended below them are pockets 70 F², of any textile material, having small openings F³ in the bottom for the removal of dust, dirt, &c., which may accumulate in them. The inner sides of the pockets are attached to the outer edges of the table by means of tacks 75 at F⁴, Fig. 2.

At the inner edge of each pocket is placed a circular wooden upright G, level with the top of the cushion and having one corner cut away to fit it around the angle of the pocket- 85 bracket. These wooden uprights are surrounded with a cushion constructed similar to the cushions before described. Centrally marked upon the board is a circle H, in the line of which are located pins H', projecting 90 above the table and surrounded by rubber tubes H² of a proper shape to form cushions like the main cushions of the table. Within this circle and concentric therewith is a second circle I, and centrally located in the center of this circle I is a small pocket K, large enough to receive one ball at a time. In front 95 of each ball-receptacle in the corners are two concentric circles J J', the inner one being not much larger than the circumference of 100 the wall, as shown.

The table, as hereinbefore described, is adapted to be played upon with balls; but in order to adapt it to be played upon with disks

slide-plates L are slidably mounted in the foundation of the table, each being provided with a knob L², projecting below the table, by which it can be moved. There are four plates 5 L, one to be arranged just inside of each pocket, and one plate L', arranged alongside of the central pocket K. Each of these plates is curved at its front end and covered with a material somewhat similar to the cover of the 10 top of the table, as at L³, Fig. 6. By grasping the knob L² and moving these plates into position, so that their front covered ends will lie in the pockets, so as to make them flat-bottomed and very shallow, the table will be 15 adapted to be played upon with disks instead of balls.

When balls are used, they are struck with cues in the same manner as billiard or pool balls, but when disks are used they are pro- 20 pelled by the fingers direct.

In Figs. 4, 5, and 7 I have shown some modifications especially adapted for tables to be used with disks. In this construction the cushions C, as well as the covering of the 25 posts or pegs G and H', are perpendicular on their inner faces, the acute-angled edge being omitted. The central pocket K is very shallow, with a flat bottom, and the outside pockets are formed of sheet metal, as at D³, 30 having a lining D⁴ of leather or other suitable material, the sheet-metal pockets being secured to the sides E of the table by means of tacks M, driven through holes inside flanges M', lying against the frame, and by tacks M² 35 through inward-projecting flanges M³ to lie against the under surface of the table.

Inasmuch as the rules of the game are the same for disks as for balls the term "balls" alone will be used in describing them.

40 Each player, of whom there may be as many as four, is provided with six balls, which lie in the corner pockets B, as shown in Fig. 1, until ready to be used. The player starts shooting by placing his ball upon the circle 45 J' and striking it with a cue. No count can be made by a direct shot; but in order to make a count a ball must, before going into the pocket, be caromed from another ball, from a side cushion, or from one of the cushions 50 H' around the centrally-arranged posts. This is the principal rule of the game, and inasmuch as no count can be made except on an angle I have denominated the game "Angulus." By making a proper carom shot a player 55 pocketing his ball is entitled to any particular number agreed upon in advance or as stated in the rules to be promulgated with

each table when sold. Counts are also to be made by leaving a ball upon a space between the circles I and H; a greater count by leaving the ball in the center pocket K. Inasmuch, however, as the specific rules of the game have no bearing whatever upon the invention, but may be varied to suit the circumstances of each case, no description of them is deemed necessary here. 60

While I have illustrated and described the best means now known to me for carrying out my invention, I wish it to be understood that I do not restrict myself to the exact details 70 of construction shown, but hold that I am entitled to any such slight changes or variations of details as would suggest themselves to the ordinary mechanic.

Having thus fully described my invention, 75 what I claim as new, and desire to secure by Letters Patent of the United States, is—

1. A table upon which balls or disks are to be impelled provided with suitable cushions and with pockets opening through said cushions, the corners of said pockets being surrounded by curved cushions extending toward the center of the table, slightly beyond the line of the cushions and slightly into the 80 pockets, thereby to prevent straight shots 85 into the pockets being made, substantially as described.

2. A table upon which balls or disks are to be impelled having marked thereon starting-points, a central pocket, side pockets, a circular series of pegs around the center pocket and obstructing-cushions at the sides of the side pockets, said obstructing-cushions being in line with the starting-points and side pockets, whereby no direct shot can be made from 95 a starting-point into a side pocket, substantially as described.

3. A table arranged to be played upon with balls, having deep pockets, and slides below the surface of the table to be pushed into the 100 pockets to cut off their lower portions and adapt the table to be played upon with disks, substantially as described.

4. A table upon which balls or disks are to be impelled provided with deep pockets, and slides for making said pockets shallow, said slides being located in the body of the table a short distance below its surface and having their forward portions covered with leather or similar material, substantially as described. 105
